UNITED STATES PATENT OFFICE

135,257

DESIGN FOR A BUILDING BLOCK

Willard A. Larson, Preston, Idaho

Application November 18, 1942, Serial No. 108,814

Term of patent 14 years

To all whom it may concern:

Be it known that I, Willard A. Larson, a citizen of the United States, residing at Preston, in the county of Franklin and State of Idaho, have invented a new, original, and ornamental Design for Building Blocks, of which the following is a specification, reference being had to the accompanying drawing, forming part thereof.

Figure 1 is a perspective view of a building block showing my new design, and

Figure 2 is a perspective view showing the opposite side and end thereof.

I claim:

The ornamental design for a building block, as shown.

WILLARD A. LARSON.
